UNITED STATES PATENT OFFICE.

SAMUEL ELIOT, OF MANCHESTER, MASSACHUSETTS.

INTERNAL-COMBUSTION ENGINE.

Application filed July 2, 1921. Serial No. 482,116.

This invention relates to internal combustion engines and is especially concerned with engines of the two-cycle type. It is the general object of the invention to devise an engine of this character which will combine in a substantial measure the advantages of a four-cycle engine with those of a two-cycle engine. In other words, the invention aims to devise an engine which will operate on the two-cycle principle and therefore have the high ratio between power and weight which these engines possess, while also having the superior scavenging, smooth operation, and reliability of four-cycle engines. Important features of the invention involve especially the mechanism for supplying the fuel mixture to the cylinders and improvements in the valve mechanism for engines of this type.

The nature of the invention will be readily understood from the following description when read in connection with the accompanying drawings, and the novel features will be particularly pointed out in the appended claims.

Referring now to the drawings,

Figure 1 is a plan view of an engine constructed in accordance with the present invention;

Fig. 2 is a view, partly in side elevation and partly in vertical cross section, of the engine shown in Fig. 1;

Fig. 3 is an end elevation of the engine shown in Fig. 1, certain parts, however, being broken away;

Fig. 4 is an enlarged plan view, partly in cross section, of the charge providing mechanism of the engine shown in Figs. 1 to 3; and

Fig. 5 is a vertical cross sectional view of the parts shown in Fig. 4.

The engine shown is of the two-cycle, two-cylinder type and comprises two cylinders designated at 2 and 3, respectively, mounted on a base 4. Pistons 6 and 7 are fitted in the cylinders 2 and 3, respectively, and are connected in the usual manner with the crank shaft 8, which is supported in the base. The cylinders are cooled in any convenient manner.

The cylinders are provided with a remov-

able cylinder head which contains or supports the charge providing mechanism and the valves. The cylinder 3 is provided with an inlet valve 10 and an exhaust valve 12, both these valves being of the poppet type and ground into their seats in the usual manner. The inlet valve 10 is normally held in its closed position by a relatively light spring 14 which encircles the valve stem and bears against a washer which is backed up by a nut 15 threaded on to the stem so that the pressure of the spring can be readily adjusted. The cylinder 2 is provided with corresponding valves designated at 10' and 12', respectively.

The ports controlled by the valves 10 and 10' open into opposite sides of a semi-circular casing or chamber 16 which is formed integral with or secured rigidly to the cylinder head. An oscillating vane or plate 17 fits snugly within the walls of this chamber and is secured fast to a shaft 18 that projects across the cylinder head and has a pinion 19 secured fast thereto, the shaft being supported in suitable bearings to oscillate back and forth through an arc of nearly 180°. This oscillating movement is produced by a rack 20 guided vertically in the engine frame and driven by an eccentric strap 22, Fig. 3, which is operated by an eccentric 23 mounted fast on the cam shaft 24 of the engine. This cam shaft is driven through a gear connection 25, Figs. 2 and 3, with the crank shaft 8. The connections just described thus swing the plate 17 back and forth from one limit of its stroke to another in a definite time relationship to the rotation of the crank shaft 8.

A carburetor 27 which may be of any suitable type is connected to one side of the cylinder head at 28, Figs. 4 and 5, and this head is provided with diverging passages 29 and 30 which lead from the carburetor to points directly under opposite sides of the floor of the chamber 16. Communication between these passages and the chamber is controlled by valves 31 and 32, respectively, each held in its seat by a light spring 33 which can be adjusted in the same manner that the spring 14 is adjusted.

It will now be evident that when the plate

17 swings in the direction indicated by the arrow in Fig. 5, it will draw a charge from the carburetor through the passage 30 and valve 32 into the right-hand side of the chamber 16, the spring 33 yielding under pressure of the incoming fuel mixture. As soon as, or before, the plate 17 starts to swing in the opposite direction, the valve 32 will be closed by the spring 33 and the plate consequently will compress the charge previously drawn into the chamber and will produce ample pressure to unseat the valve 10 and force this charge into the cylinder 3.

10 The exhaust valves 12 and 12' are of the usual type and are mounted and operated in the same manner as such valves are operated in the ordinary overhead valve motors. That is, the valve 12 is normally held in its seat by a strong spiral spring 35, and it is 15 depressed by a rocker arm 36 mounted on a shaft 37 and operated by a thrust rod 38 carrying a mushroom that runs on a cam 39 fast on the cam shaft 24. The other valve 12' is operated in the same manner.

18 Assuming that the piston 7 in the cylinder 3 has just completed its power stroke, the parts are so timed that the exhaust valve 12 immediately opens and the scavenging stroke starts in the usual manner. While 20 this scavenging stroke is proceeding, the plate 17 is swinging toward the right, Fig. 5, and compressing a fuel mixture charge in the chamber 16. The pressure in the cylinder drops rapidly and while the piston is 25 finishing its scavenging stroke the inlet valve 10 is opened by the pressure of the gases behind it overcoming the combined pressure of the spring 14 and the pressure of the burnt gases in the cylinder 3. A fresh 30 charge immediately begins to flow through the valve thus completing the scavenging. The exhaust valve 12 is closed while the piston continues its upward stroke and thus compresses the charge which has just been 35 admitted to the cylinder. The valve 10 closes just before the pressure in the provider chamber equals the pressure in the cylinder 16. The charge then is fired by an ignition 40 system of any suitable type but timed on the two-cycle principle, the power stroke takes place and the operations just described are 45 repeated. The same operations of course also take place in the other cylinder 2, the power strokes in the two cylinders alternating in the usual manner.

50 It will now be appreciated that the invention provides an engine operating on the two-cycle principle but which overcomes many of the disadvantages of the prior two-cycle engines. It will also be appreciated that a very complete scavenging is obtained in an engine of this construction, and that the location of the provider and its method of operation produces a very complete mixing of the air and fuel vapors before they

are introduced into the cylinder and thus materially improves the condition of the charge. In other words, it produces superior carburetion.

55 It will be observed that an engine of the construction herein disclosed lends itself particularly well to the flame type of ignition system in which the flame is admitted from one cylinder to another to fire the charge.

70 The disclosure herein made sets forth the fundamental features of the present invention in the best form which I have so far devised, but it should be understood that this disclosure is made rather by way of illustration than limitation, and that the invention may be embodied in many forms and designs differing substantially in details of construction from the design herein illustrated.

75 What is claimed as new is:

1. An internal combustion engine of the two-cycle type having means secured to the engine cylinder for supplying a fuel mixture under pressure to said cylinder, said means including an oscillating plate for creating said pressure.

2. An internal combustion engine of the two-cycle marine type having a carburetor, a mixing chamber on the cylinder head having connections at opposite sides thereof with said carburetor, said connections including check valves preventing the flow of fuel mixture from the chamber to the carburetor but permitting such flow in the opposite direction, a device mounted to swing backward and forward in said chamber to draw a charge from the carburetor into one side of the chamber and simultaneously to compress the charge in the opposite side of said chamber, connections between the opposite sides of said chamber and the engine cylinders through inlet valves for admitting the compressed charge to the engine cylinders, and mechanism driven from the crank shaft of the engine and independent of the engine pistons for operating said device.

3. An internal combustion engine of the two-cycle marine type having an inlet port in the upper part of each cylinder, a spring operated valve for opening and closing said port, a fuel mixing chamber into which said port opens, a carburetor connected with said chamber, a pivoted device operative in said chamber to draw a charge of fuel mixture from said carburetor and compress it to a point causing it to open said valve, an exhaust valve in each cylinder, and connections for utilizing the power of the crank shaft to operate said device and said exhaust valve.

4. An internal combustion engine of the two-cycle marine type having an inlet port in the upper part of each cylinder, a spring operated valve for opening and closing said

port, a charge provider mounted on the cylinder head and having a fuel mixing chamber into which said port opens, a carburetor connected with said chamber, a swinging device operative in said chamber to draw a charge of fuel mixture from said carburetor and compress it to a point causing it to open

said valve, an exhaust valve in each cylinder, connections for utilizing the power of the crank shaft to operate said device, and 10 additional connections with said crank shaft for operating said exhaust valve.

SAMUEL ELIOT.
